UNITED STATES PATENT OFFICE

2,304,841

ARTILLERY TRAINER

Harry E. Mikkelsen, United States Army,
West Point, N. Y.

Application September 27, 1941, Serial No. 412,611

4 Claims. (Cl. 124—11)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to an artillery trainer "firing" device.

An object of this invention is to provide a pneumatic artillery trainer which requires no expenditure of ammunition.

Another object of this invention is to provide an artillery trainer which requires substantially no cleaning since no powder fouling occurs.

Another object of this invention is to provide an artillery trainer of high accuracy and low dispersion and one which allows a good reproducibility of projectile motion.

Another object of this invention is to provide an artillery trainer which is easy to calibrate and which maintains its calibration during the course of "firing" the trainer.

Another object of this invention is to provide a pneumatic artillery trainer "firing" device which may be easily adjusted for range.

An artillery trainer is described in this application that is an improvement over the one described in an article by H. G. Bishop on page 419 of "The Military Engineer" for September-October 1933; the gun described in that article is shown in U. S. Patent 2,003,290, Gurney et al., issued June 4, 1935. The apparatus described in this application was designed to overcome disadvantages inherent in the apparatus described in the above mentioned prior art; in actual "firing" the apparatus described herein is superior to the prior art apparatus in accuracy, permanency of calibration, ease of cleaning, reproducibility of results, and rapidity of "fire."

The specific nature of the invention as well as other objects and advantages thereof will clearly appear from a description of a preferred embodiment as shown in the accompanying drawings in which:

Fig. 1 discloses a schematic view of the pneumatic system in which the artillery trainer "firing" device is incorporated.

Fig. 2 is a view in side elevation of a mount for the pneumatic "firing" device.

Fig. 3 is a rear elevation of the mount shown in Fig. 2.

Fig. 4 is a perspective view of the assembled pneumatic firing device detached from its mount.

Fig. 5 is a view taken substantially on line 5—5 in Fig. 4 and shows a section through the gun tube with the projectile P in "firing" position.

Fig. 6 is a view taken substantially on line 6—6 in Fig. 4 and shows a section through the air chamber, the supporting rod 34c and filling means 34b.

Fig. 7 is a view taken substantially on line 7—7 in Fig. 4 and shows a section through the quick operating valve.

Fig. 8 is a view taken substantially on line 8—8 in Fig. 4 and discloses the manner in which the trigger is mounted on the operating handle of the quick operating valve.

Fig. 9 is a plan view of the quick operating valve.

Fig. 10 is a section substantially through the center of the valve and discloses the manner in which the shaft 40 is connected to the movable portion of the valve.

Fig. 11 discloses a conventional automobile tire check valve (without spring) in the inlet to the gas chamber 34.

Description of the gun mount

Referring to the drawings by numeral of reference:

25 There is provided a bottom carriage 1 adapted to be bolted or otherwise secured to a base 2 as by the bolts 3.

Mounted on the bottom carriage 1 for rotation about a pintle 4 is a top carriage 5 of any preferred form but herein shown as consisting of side standards 6—6, connected at their base by a plate or web 7. Means for traversing the top carriage is provided, a simple form herein shown consisting of a pedestal 8 at the top of which is provided a bearing for a traversing screw 9 which engages in a nut 10 on the top carriage. The traversing screw may be operated through means of a handle 11.

40 Journaled in the top carriage by means of the shaft 12 is an angle of site bracket 13 which may be rocked on said shaft to set in angle of site through means of an angle of site screw 14 suitably journaled at 15 in the top carriage and engaging a nut 16 on the bracket. The bracket 45 may be formed with a rest 17 for a gunner's quadrant, and with a rearwardly extending arm 18 carrying an index 19 for the elevation scale 20. The bracket terminates at its upper end in a suitable support for a sight 21.

Mounted to rock about the same axis as that of the bracket is a cradle having a downwardly and rearwardly extending portion 23 in which is journaled an elevating screw 24 in engagement with a nut 25 on the bracket 13. The elevating screw may be conveniently operated through the

handle 26. The cradle may have attached thereto a seat 27 for a gunner's quadrant and is formed with a suitable support 22 for the reception of the pneumatic gun. An arm 29 extends upwardly from the cradle to mount the elevation scale 20.

The gun support 22 is preferably in the form of a tubular member in which the gun tube 37 of the pneumatic gun has a free sliding fit. The gun tube 37 is firmly held by suitable means as by providing a knurled screw 31 which is adapted to clamp the gun tube 37 at the reduced portion 37a (Fig. 5); shoulders 37b are adapted to cooperate with the screw 31 so as to maintain the gun tube in the mount within a predetermined range. To aid in supporting the gun and to hold it while adjusting the gun tube 37 to vary it within that predetermined range, an extension 34d on the gas chamber 34 is provided to abut one of the side standards 6 along a line contact. Since the extension 34d is cylindrical and since the correspondingly situated side standard 6 has a flat surface, a line contact between extension 34d and standard 6 must necessarily exist when those two elements abut one another along the length of the extension 34d. The extension 34d is shaped and has such a length that movement of the gun tube a distance between its shoulders 37b will always find the extension 34d in contact with standard 6.

Description of the pneumatic gun

The pneumatic gun is made up largely from the following essential elements: a gas chamber 34, quick acting valve 35, tube 36, gun tube 37, and locking ring 38. The gas chamber 34 is in communication with the quick acting valve 35 by means of the nipple 34a and street-L 35a. Tube 36 is in communication and joined with the other side of the quick acting valve 35 by means of conventional pipe threads on street-L 36a; tube 36 also has a finer threaded portion 36b upon which the knurled gun tube 37 is adjustably positioned. The knurled locking ring 38 serves to hold the gun tube 37 in adjusted position on tube 36.

The gas chamber 34 has a pneumatic inlet valve stem 34b which may partake the form and size of the conventional automobile tire tube valve stem. A springless Shrader valve 34e is disposed in the valve stem 34b (Fig. 11). A rod 34c is fastened at one point on the gas chamber 34 and bent so as to form a straight portion 34d which abuts one of the standards 6 on the gun mount along a line contact so that the gun is prevented from rotating in the gun cradle and yet allows an easy movement of the gun along its axial direction as the gun is adjusted in its cradle.

The quick acting valve 35 is of the type wherein in rotation of its handle 39 through a small angle results in opening or closing the valve. The handle 39 is mounted on shaft 40 which is connected to a pivotable closure member 35b through a pin and slot connection 35c between arm 35d on shaft 40 and extension 35e on closure member 35b. The closure member 35b is adapted to open due to pressure in the space 35f (Fig. 10).

In order to insure that the valve is opened at the same rate each time the gun is fired, a trigger 45 is pivotally and spring-biased on the plate 46 which has an offset portion 47 held by one of the valve bolts 48. The trigger arm 49 is adapted to abut the projecting portion 50, at 55, on the valve handle in a resilient manner due to the handle spring 51 which has one end fixed rela-

tive to the valve body at 52 (Fig. 8) and the other end encircling the valve handle 39. A stop 53 on the fixed plate 46 limits the movement of the trigger 45 and serves to hold the trigger arm 49 in abutting relationship with the handle projection 50. The trigger spring 54 normally holds the trigger against the stop 53 and the trigger is displaced from that position a small amount as the valve handle is rotated bodily to its closed position whereby the trigger arm 49 is allowed to fall into the small detent 55 in the handle projection 50.

If desired a quick acting magnetically operated valve may be substituted for the mechanical valve shown in the drawings.

The pneumatic gun is disposed in the pneumatic system as shown in Fig. 1. In the particular arrangement, compressed air under a pressure of about 100 lbs. per sq. in. from tank A is piped to an air regulating valve B which is capable of supplying air at a certain set pressure at all times, provided the pressure in tank A is kept somewhat above 45 lbs. per sq. in. The air regulating valve B is connected to the gas chamber 34, which in turn is connected to the gun tube 37 in a manner described above. Between the gas chamber 34 and the gun tube 37 is the quick opening valve 35 which, when opened, allows the air under pressure in tank 34 to blow out the projectile P from the gun tube 37. The air regulating valve B serves to maintain the pressure in the gas chamber 34 at a constant value; this valve may partake of a variety of forms and shapes and is used extensively in pneumatic distribution systems. Other "guns," similar to the one described, may be supplied from valve B, as indicated by the dotted lines in Fig. 1, when the "guns" are supposed to constitute an artillery "battery."

In order to adjust the range of the gun the following steps are taken:

1. Release the knurled locking ring 38.
2. Loosen screw 31. (Fig. 5.)
3. Rotate gun tube 37 with respect to tube 36 the required amount and/or slide gun tube 37 in its cradle.
4. Rotate the locking ring 38 into locking position.
5. Tighten screw 31.

But for the rod-shaped projections 34d on the gas chamber 34, the gun would inconveniently rotate during the above adjustment operation; the projection 34d makes a line contact with the standard 6 so that the gun may be bodily moved in its cradle without imparting any rotation to the gun. Besides being convenient in allowing an adjustment to be made with one hand, this feature is important because the gun is moved only in one of the three dimensions and thus allows the gun to be sighted rather quickly.

The unit shown in Fig. 4 may have its range varied to predetermined fractions of the ranges of pieces of standard artillery by simply increasing the pressure of the air in chamber 34 and/or changing the volume in the gun tube included between the free end or muzzle of the gun tube 37 and the end of tube 36 upon which the ball projectile P is adapted to rest; that volume is changed by simply unlocking ring 38 and turning gun tube 37 with respect to tube 36.

I claim:

1. A unit adapted to fire projectiles predetermined fractions of the ranges of pieces of standard artillery for training an artillery gun crew

embodying a gas chamber, a tube, a quick acting valve joining the chamber and the tube, said tube having its free end adapted to abut against a ball projectile whereby the free end is sealed, a gun tube coaxially mounted on the tube, means for adjusting the relative position of the gun tube and tube, means for locking the tubes in adjusted position; a gun mount embodying a hollow portion adapted to snugly receive the gun tube, said gun tube having a grooved surface, a screw threaded in the gun mount and projecting into said grooved surface, said screw serving as a combination stop and lock element for movement of the gun tube.

2. A unit adapted to fire projectiles predetermined fractions of ranges of pieces of standard artillery for training an artillery gun crew embodying a gas chamber, a tube, a quick acting valve joining the chamber and the tube, a gun tube coaxially mounted on the tube, said chamber, tube, valve and gun tube disposed in a U shape, said gun tube having a cylindrical outer surface adapted to receive a clamp, a projection on the gas chamber; and a support having a clamp for said gun tube cylindrical outer surface and having a flat surface for engagement of said projection along a line contact.

3. A U-shaped unit adapted to fire projectiles

5 predetermined fractions of ranges of pieces of standard artillery for training an artillery gun crew embodying a gas chamber forming one of the parallel legs of the U, a tube, a gun tube coaxially mounted on the tube, said tube and gun tube forming the other parallel leg of the U, a quick acting valve joining the chamber and the tube and forming the horizontal portion of the U, an operating handle for the valve projecting beyond the confines of the U, said gun tube having a cylindrical clamping surface, and a projection on the gas chamber adapted to make contact with a support along a line parallel to the parallel legs of the U.

10 4. In combination, a gun mount embodying a base, a top carriage on the base, a cradle carried by the top carriage, a gun support on the cradle, a U-shaped gun having a cylindrical clamping surface on one of the parallel legs of the U and having a cylindrical projection on the other parallel leg of the U, said top carriage having an outer flat surface extending vertically and parallel to the parallel legs of the U, means for clamping the cylindrical clamping surface in the gun support, and said cylindrical projection making a 20 25 line contact with the flat carriage surface.

HARRY E. MIKKELSEN.
